UNITED STATES PATENT OFFICE.

ORAMEL ERNEST HIBBARD, OF GREENWICH, OHIO.

PAPER CLIP.

Application filed October 26, 1923. Serial No. 670,925.

To all whom it may concern:

Be it known that ORAMEL E. HIBBARD, a citizen of the United States, residing at Greenwich, in the county of Huron and State of Ohio, has invented certain new and useful Improvements in Paper Clips, of which the following is a specification.

This invention has reference to paper fasteners and provides an improved fastener presenting means for pinning together two or more papers in a firm and secure manner and without causing any undue mutilation or destruction of the papers.

A further and additional object is to provide a paper fastener including a fastening pin and a guide between which the papers are adapted to be clamped, the said guide being provided with socket means for receiving the pointed end of the pin.

Various other objects and advantages of the invention may become apparent from the following disclosure.

In the drawing:

Figure 1 is a view disclosing the manner of applying the invention in practice,

Figure 2 is a top plan view of the proposed paper fastener,

Figure 3 is a sectional view taken along line 3—3 of Figure 1, and

Figure 4 is an end elevation of the structure shown in Figure 3.

In constructing the improved fastener, the same is preferably formed of two parts, namely, a fastening pin and a guide therefor. The pin, indicated at 10, is preferably formed of broom wire presenting an elongated shank having pointed end 11 and a flat head 12.

The guide may be constructed of sheet metal and consists of a flat elongated strip of narrow width, as indicated at 13 bent upwardly at the end 14 and provided with an eye 15 of suitable diameter to permit the shank of the pin to pass easily therethrough. At its opposite end, the strip is provided with turned up portions 16 and 17 presenting a tubular sleeve or socket for the reception of the pointed end of the pin, as

shown in Figure 1. In practice, the papers 18 and 19 to be fastened together are placed against guide 13 which is slightly arched to present inclined sides, as shown in Figure 3, so as to permit the formation of a slight depression in the papers, as indicated at 20.

Pin 10 is then inserted thru eye 13 of the guide until the pointed end 11 punctures the paper at 21 and 22, the point of the pin passing rearwardly of the papers and engaging in the sleeve formed by turned up portions 16 and 17. The depressed portions of the papers will thus be firmly clamped between the flat guide 13 and the shank of the pin, as shown in Figure 3, the pressure of the depressed portions 20 of the papers against the shank of the pin serving to retain the latter firmly in place.

It will thus be seen that the invention provides a paper fastener of simple construction and which can be readily applied to or removed from a set of papers, it being further observed that the latter are penetrated only at two points. The perforations are merely pin holes of small degree and consequently do not tend to disfigure the papers or cause them to present a mutilated appearance from the fastener.

From the foregoing it is thought that the advantages and novel features of the invention can be readily understood and that further detail description thereof is not required.

What is claimed is:

A paper fastener consisting of a fastening pin and a sheet metal guide arched to provide inclined sides permitting the formation of a slight depression in the papers to be fastened, the said guide having an upturned portion at one end provided with a central opening to receive the shank of the fastening pin and having portions at its opposite end turned inwardly to provide a tubular sleeve for the reception of the point of the said pin.

In testimony whereof I affix my signature.

O. ERNEST HIBBARD.
